UNITED STATES PATENT OFFICE

MAYHUGH M. MEADOWS, OF LAWTON, OKLAHOMA

CLOTHES RACK

Application filed July 14, 1931. Serial No. 550,753.

This invention relates to new and useful improvements in clothes racks, and the principal object of the invention is to provide a rack of the collapsible type, which when not in use can be collapsed to assume a position requiring the minimum amount of space.

Another important object of the invention is to provide a collapsible clothes line which can be easily extended to supporting position without any excessive exertion on the part of the person manipulating the same.

Other important objects and advantages of the invention will become apparent to the reader of the following specification.

In the drawings:

Figure 1 represents a top plan view of the rack in extended position.

Fig. 2 represents a vertical sectional view through the rack.

Fig. 3 represents a transverse sectional view through one of the extended portions taken substantially on the line 3-3 of Fig. 1.

Fig. 4 represents a horizontal sectional view taken substantially on the line 4-4 of Fig. 2.

Referring to the drawings wherein like numerals designate like parts, it can be seen that numeral 5 represents an upstanding post, the lower end portion of which can be anchored to the ground or secured otherwise to a supporting body. A square-shaped plate 6 is secured at its central portion to the top of the post 5, by a suitable detent 7, and each edge portion of this plate 6 intermediate the corners thereof is provided with a notch 8 in which the inner end of an elongated arm 9 is pivotally secured as at 10 to the aforementioned plate 6.

A bar 11 extends transversely through each arm 9 and projects an equal distance beyond said side of the arm. Brace means 12 can be provided between the outer end of the arm 9, and the ends of the bars 11 and interposed between eyes 13 on the plate 6 and each bar 11 are the strands, rods or the like, over which clothes to be dried can be hung.

A collar 15 preferably of square cross section to accommodate the square post 5 is slideable on the post 5. A brace member 16 is provided for each arm 9, the upper end be-

ing pivotally connected to the arm as at 17, while its lower end is pivotally connected as at 18 to the upper end of the collar 15.

Handles 19-19 extend laterally from the collar 15 in opposite directions with respect to each other, and each is provided with a longitudinally extending slot 20 therein. Rockably mounted in each slot 20 is a claw 21 provided with a tooth-shaped lower end 23 which can bite into the post 5, and does bite into the post 5 by the tensional action of the spring 22, which is interposed between the upper end of each claw 21 and corresponding handle 19.

L-shaped rocker arms 24 are also located on the handles, one for each of the claws 21. One end of this L-shaped member 24 serves as a handle, while the opposite end to the corresponding claw 21 by a pivotal link 25.

It can now be seen, that when the collars are in the position shown in Fig. 2, with the arms 9 raised to a horizontal position, and it is desired that the arms 9 be lowered, the handles 19-19 are grasped, and by pressing the fingers against the rockable members 24, a pull will be exerted on each of the claws 21 so as to release the claws from the post 5, whereupon the collar can be pulled down by the handle 19 so that the arms 9 and the collar, and its associated details will assume the dotted line position shown clearly in Fig. 2.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:

A clothes rack of the character described comprising a post, a plurality of arms radiating from the post and being swingably connected thereto, a collar vertically slideable on the post, a handle on the collar, claw means between the handle and the said post whereby the collar can be retained in adjusted position on the post, said handle being provided with a longitudinally extending slot therein, a swingable claw member rockable on the handle and in the slot and being en-

gageable with the post, spring means interposed between the claw member and the handle for normally maintaining the claw member engaged with the post, and a rockable arm on the handle within the slot and a connection between the arm and the claw member whereby the claw member can be disengaged from the post.

In testimony whereof I affix my signature.
